(57) **CLAIM**

The ornamental design for a segment handle, as shown and
described.

DESCRIPTION

FIG. 1 is a front elevation view of a segment handle, showing my new design;

FIG. 2 is a rear elevation view thereof;

FIG. 3 is a left side perspective view thereof, the right side
being an identical image thereof;

FIG. 4 is a bottom perspective view thereof; and,

FIG. 5 is a top perspective view thereof.

The broken lines on claimed surfaces depict stitching and
form no part of the claim. The broken lines showing portions
of a bag in FIGS. 1 and 2 depict environment and form no
part of the claim.

The SEYER logos are a registered trademark of SEYER
GmbH and form no part of the claim.

1 Claim, 5 Drawing Sheets
